UNITED STATES PATENT OFFICE.

JOSEPH F. LUDLAM, OF BROOKLYN, NEW YORK.

DESIGN FOR A WATCH-CASE.

SPECIFICATION forming part of Design No. 12,228, dated April 19, 1881.

Application filed February 18, 1881. Term of patent 7 years.

To all whom it may concern:

Be it known that I, JOSEPH F. LUDLAM, of Brooklyn, in the county of Kings and State of New York, have invented a Design for Watch-Cases, of which the following is a specification.

In the drawings, Figure 1 is a perspective view of my newly-designed watch-case, and Fig. 2 is a transverse section.

10 Similar letters of reference indicate corresponding parts.

The distinguishing features of the design are the scalloped beveled portions *a* and raised ornamental beads *b* on the rim of the caps. 15 The beads *b*, which may have a surface ornamentation of any desired character, form the rims or edges of the caps, and project, when the case is closed, above the surface of the ring-case. The beveled portions *a* join the 20 beads and are fluted in the direction of the bevel, so that the angles present a scalloped outline. The basket-work ornamentation of the case is between the beads *b* on the surface

or periphery of the ring-case, which is sunken by the projection of the beads at each side. 25 The surface of the caps within the beveled edge may be ornamented, as desired.

I am aware that beads or knurls have been applied to the edge of watch-caps. Such I do not claim.

Having thus described my invention, I claim as new and desire to secure by Letters Patent—

1. The design for watch-cases, consisting of the fluted or scalloped bevel portion *a* and 35 beads *b*, forming the edges of the caps, as shown and described.

2. The design for watch-cases, consisting of the fluted bevel portion *a* and beads *b* of the caps, in connection with the basket-ornamentation *c* on the periphery of the case, as shown and described. 40

JOSEPH F. LUDLAM.
